(57) **CLAIM**

The ornamental design for an imaging device with a housing, as shown and described.

DESCRIPTION

This patent contains a drawing executed in color. Copies of this patent with the color drawing will be provided by the Office upon request and payment of the necessary fee.

FIGURE is a top plan view of an ornamental design for an imaging device with a housing.

The ornamental design that is claimed is shown in solid lines in the drawing. The broken lines in the drawing show portions of an imaging device with a housing that form no part of the claimed design. The dash-dash broken lines in the drawing are included for environmental purposes only and form no part of the claimed design. The dash-dot broken lines in the drawing are included to define boundaries of the claim only and form no part of the claimed design.
